UNDERFEED STOKER

Filed Dec. 31, 1921

Robert Sanford Riley INVENTOR.

BY

Southgate & Southgate ATTORNEYS.

UNITED STATES PATENT OFFICE.

ROBERT SANFORD RILEY, OF WORCESTER, MASSACHUSETTS, ASSIGNOR TO RILEY STOKER CORPORATION, A CORPORATION OF MASSACHUSETTS.

UNDERFEED STOKER.

Application filed December 31, 1921. Serial No. 526,288.

This invention relates to a furnace stoker of the underfeed type in which fuel is fed into rearwardly and downwardly inclined retorts which discharge ash and refuse from 5 the rear ends thereof.

One object of my present invention is to provide for entirely separate and independent control of the air supplied to the fuel retort side walls and to the overfeed grate 10 section at the rear and below said side walls. It has been heretofore customary to provide means for decreasing the air pressure on the overfeed grate below that of the side wall pressure when desired, but it has been 15 impossible to independently decrease the air pressure on the side walls without at the same time reducing the pressure on the overfeed grate.

Independent regulation of the pressure at 20 these different points renders possible a much more efficient operation of the furnace, as the air may be closely regulated to the condition of the fire and the depth of the fuel bed at different points in the furnace.

25 A further object of my invention is to provide additional means for separately controlling the air supply to each overfeed grate section in a multiple retort stoker. This also makes for efficiency of operation as it 30 permits the air pressure to be reduced whenever a thin place occurs in the fuel bed on a particular overfeed grate section.

A further object is to provide an air admitting dump plate at the rear of the retort, 35 pivotally mounted on the bridge wall and extending closely adjacent the rear edge of the reciprocating overfeed grate. This dump plate may be made in sections and I provide means by which selected sections 40 of the dump plate may be moved independently of other sections thereof.

With these and other objects in view, my invention further relates to arrangements and combinations of parts which will be 45 hereinafter described and more particularly pointed out in the appended claims.

A preferred form of my invention is shown in the drawings, in which

Fig. 1 is a vertical longitudinal section 50 of my improved stoker, taken substantially along the center line of a retort;

Fig. 2 is a partial plan view thereof; and

Fig. 3 is a vertical transverse section taken along the line 3—3 in Fig. 1.

55 Referring to the drawings, I have shown

parts of an underfeed stoker of a well known commercial type, said stoker comprising a hopper 10 from which coal is fed to a cylinder 11 connected to a stoker retort by a feed chute or casing 12 extending through 60 the front wall 13 of the furnace. A ram 14 is slidably in the cylinder 11 and is regularly reciprocated by a crankshaft 15 rotated by suitable driving mechanism including a worm 16 and worm wheel 17. The worm 16 is continuously rotated by suitable driving connections, not shown.

The fuel retorts have a trough-like or U-shaped section and are shown herein as provided with air-admitting side walls 20 slidably longitudinally of the retort and receiving motion from the ram 14 through lost motion driving connections 21. Overfeed grate sections 22 are disposed below and at the rear of the side walls 20 and are preferably connected for reciprocation therewith.

An air trunk 23 extends beneath the several retorts of the furnace and is supplied with air under pressure from a fan 24 or 80 in any other desired manner. Air chambers 25 and 26 are formed under the stokers, each chamber being directly connected to the air trunk 23 by short passages controlled by the dampers 27 and 28.

85 The air chamber 25 is connected through passages 25^a to the interior of the side walls 20, through which the air passes to the tuyère blocks 29 by which the air is admitted to the fuel in the retort. For a more complete disclosure of the details of this part of the stoker, reference is made to my prior Patent, No. 1,090,651, issued March 17, 1914.

The retort walls are supported upon plates 30 extending lengthwise of the retorts and at their lower ends these plates form the sides of air passages to the different overfeed grate sections 22. A damper 31 is mounted in each of these air passages to control the flow of air to the corresponding 100 overfeed grate section. These dampers 31 are preferably supported on arms 32 loosely pivoted on brackets or bearings 33 extending into the air chamber 26. The separate dampers 31 may each be provided with 105 an operating link or rod 34 extending to the front of the stoker and having a plurality of notches 35 adapted to be engaged by a keeper 36 to prevent displacement from a desired adjusted position.

With this construction, it is possible to regulate the air pressure in either of the air chambers 25 or 26 by means of the dampers 27 and 28 and it is also possible to control the flow of air through a particular overfeed grate section by adjusting the associated damper 31. The flow of air may be thus regulated in accordance with the conditions at different points in the fuel bed. Should a thin place occur the air may be reduced or entirely shut off and should the fuel bed build up to unusual thickness the air pressure at that particular point may be correspondingly increased.

At the rear of the furnace I have shown an air-admitting dump plate 40, preferably pivoted upon an air casing 41 positioned below the back or bridge wall 42 and partially supporting the same. The casing 41 is connected by a pipe or conduit 43 to the main air trunk 23 and is provided with a damper 44 by which the air pressure on the dump plate 40 may be controlled.

The dump plate is preferably made in sections corresponding in number to the number of retorts and each section is provided with a depending arm or bracket 45 connected by a link 46 to a crank pin 47 on an arm 48 fixed to a crankshaft 49. The crankshaft 49 is preferably formed in short sections as indicated in Fig. 2 and each section of the shaft may be of greater or less length and may be manually rotated by means of a hand wheel 50 positioned behind the wall 42 and connected through a worm 51 and worm wheel 52 to the crankshaft section 49.

As shown in the drawings, two dump plates 40 are arranged for operation by each hand wheel 50 but it will be understood that this particular arrangement of the parts may be varied to suit the conditions in a particular stoker. The dump plates 40 are preferably provided with air admitting openings 53 in their bearing portions and the upper part of each dump plate is formed as a grate having the usual air passages between the elements thereof.

Having described the details of construction of this form of my improved stoker, the method of operation will be readily apparent. The fresh fuel is fed into the bottom of each retort at its upper or front end and is gradually worked rearward by the movement of the reciprocating side walls 20 and by the continued action of the feeding ram 14.

As the fuel reaches the lower rear portion of the retort, its rearward movement is continued by the action of the reciprocating overfeed grate sections 22. The ash and refuse are deposited upon the dump plates 40 and the combustion of any unconsumed fuel therein will be made complete by the air entering through the grates of the dump plates.

When the amount of ash deposited on any particular section of the dump plates becomes excessive, the plates are lowered by means of the hand wheel 50 and the ash and refuse is deposited in the ash pit.

70

Having thus described my invention, it will be evident that changes and modifications can be made therein by those skilled in the art within the spirit and scope of my invention as set forth in the claims and I do not wish to be otherwise limited to the details herein disclosed but what I claim is:

75

1. An underfeed stoker comprising bottoms, and longitudinally movable side walls, forming parallel underfeed retorts extending in the direction of fuel travel, movable, air admitting overfeed grates, forming extensions of the retort bottoms, tuyères surmounting the movable side walls, a dump plate in the rear of the overfeed grates, 80 means defining an air trunk, means including a partition wall separating said tuyères from the overfeed grates so that air may be supplied independently to each, and means for independently regulating the 85 flow of air to the tuyères and to the overfeed grates.

90

2. An underfeed stoker comprising bottoms, and longitudinally movable side walls, forming parallel underfeed retorts extending in the direction of fuel travel, air admitting movable overfeed grates, forming extensions of the retort bottoms, tuyères surmounting the movable side walls, an air admitting dump plate in the rear of the 100 overfeed grates, means defining an air trunk, means including a partition wall separating said tuyères from the overfeed grates so that air may be supplied independently to each, and independent means for 105 regulating the flow of air to the tuyères, to the overfeed grates, and to the dump plate.

95

3. An underfeed stoker comprising bottoms, and side walls forming parallel underfeed retorts extending in the direction of 110 fuel travel, air admitting overfeed grates, forming extensions of the retort bottoms, tuyères surmounting the side walls, a dump plate in the rear of the overfeed grates, means forming an air trunk, means including partition walls separating said tuyères from the overfeed grate, and means including dampers for regulating the admission of air to said tuyères and to the overfeed grates independently of each other, whereby the 120 air pressure to the tuyères may be controlled and regulated independently of the air pressure to the overfeed grates.

115

4. In an underfeed stoker, a plurality of fuel retorts having air-admitting side walls, 125 means for supplying air thereto, a movable overfeed grate section at the rear of each retort, means for supplying air thereto, means to control the flow of air to the retort side walls, independent means to control 130

the flow of air to the overfeed grates, and supplementary means to separately control the flow of air to each overfeed grate section.

5 5. In an underfeed stoker, a plurality of fuel retorts having air admitting side walls, means for supplying air thereto, a plurality of overfeed grate sections, one at the rear of each retort, means for supplying air to said grate sections, means to control the flow of air to the retort side walls, and separate means to control the flow of air to each overfeed grate section, whereby the air pressure in the overfeed grate section at the rear of a selected retort may be made equal to, greater than, or less than the air pressure in said retort side walls.

6. In an underfeed stoker, a plurality of fuel retorts having air admitting side walls, means for supplying air thereto, a plurality of movable overfeed grate sections, one at the rear of each retort, means for supplying air to said grate sections, means to control the flow of air to the retort side walls, and separate means to control the flow of air to each overfeed grate section, whereby the air pressure in the overfeed grate section at the rear of a selected retort may be made equal to, greater than, or less than the air pressure in said retort side walls. 20 25 30

In testimony whereof I have hereunto affixed my signature.

ROBERT SANFORD RILEY.
